UNITED STATES PATENT OFFICE.

GEORGE W. CONNOR, OF ANDERSON, SOUTH CAROLINA.

APPARATUS FOR DEVELOPING POWER.

1,332,804.

Specification of Letters Patent.

Patented Mar. 2, 1920.

Application filed May 12, 1919. Serial No. 296,501.

To all whom it may concern:

Be it known that I, GEORGE W. CONNOR, a citizen of the United States, residing at Anderson, in the county of Anderson and State 5 of South Carolina, have invented new and useful Improvements in Apparatus for Developing Power, of which the following is a specification.

The object of my present invention is to 10 utilize the expansion of fluid under pressure preferably gases, to the best advantage in the actuation of a driven element, preferably a rotor.

The invention consists in an apparatus 15 embodied in which is a compressor and retarding means for coöperation with the compressor in the initial compression of the fluid, in combination with a rotor of such character that the fluid is secondarily compressed thereagainst precedent to the utilization 20 of the expanding fluid for the driving of the rotor. The apparatus also comprises a peculiar and advantageous rotor against which the expanding fluid acts in a continuing 25 operation; an arrangement whereby the atmospheric air supplied to the carbureter of the apparatus is heated by the combustion in the apparatus to improve the expanding quality of the fluid and at the same 30 time such air is used for cooling purposes; a combination whereby a plurality of volumes of expanding gases are provided for the propulsion of the rotor during the turning thereof, through each revolution; and 35 a combination whereby the compressor, rotor, retarding valve and magneto are all timed together, and are so relatively arranged that they cannot get out of time.

Other novel features of the invention are 40 developed in the following description and claims, reference being had to the accompanying drawings forming part hereof, in which:

Figure 1 is a plan view of the apparatus 45 constituting the best practical embodiment of the apparatus part of my invention that I have as yet devised.

Fig. 2 is an elevation taken at right angles to Fig. 1.

Fig. 3 is a view partly in plan and partly 50 in section, with the upper portion of the casing removed.

Fig. 4 is a section taken on the line 4—4 of Fig. 5.

Fig. 5 is an enlarged transverse section 55 taken in the plane of the line 5—5 of Fig. 3,

Figs. 6 and 7 are transverse sections taken on the lines 6—6 and 7—7, respectively, of Fig. 4.

Fig. 8 is a side elevation of one of the 60 disks comprised in the rotor construction.

Fig. 9 is an enlarged detail section through the retardation valve.

Fig. 10 is an enlarged section of the compressor comprised in the apparatus. 65

Similar numerals of reference designate corresponding parts in all of the views of the drawings.

The compressor 1 is preferably, though not necessarily, of the type disclosed in my 70 Letters-Patent No. 1,283,089 of October 29, 1918, and need not therefore be specifically described except to say that the induction orifice of the compressor is at 2 and the eduction orifice thereof at 3. A conduit 4 75 connects a carbureter 5 with said induction orifice 2, and a conduit 6 leads from the eduction orifice 3 to the casing of a rotary retarding valve 8 having ports 9 that describe parts of a circle, Fig. 9, and are adapted to 80 effect communication between the conduit 6 on the one hand, and a port 10 on the other; the said port 10 being in communication with a combustion chamber 11. Also in communication with said combustion chamber 11 are two spark plugs 12. Practically surrounding the combustion chamber 11 but not in direct communication therewith is an air conduit 13, Fig. 5, which is joined to a conduit 14 which, together with the conduit 90 13, extends almost half-way around the casing 15, which is preferably circular in form and in two sections as illustrated. Air induction ports 16, grouped about the combustion chamber 11, Figs. 2 and 5, lead from 95 the atmosphere to the chamber-surrounding conduit 13, and the end of the conduit 14 remote from said conduit 13 is connected through a conduit 16^a with the carbureter 5, as clearly appears in Fig. 1. From this it 100 follows that incidental to the operation of the apparatus, atmospheric air will be drawn in large volumes through the ports 16 and the conduits 13 and 14 into the carbureter, and in consequence the engine will be thoroughly 105 cooled by the air. At the same time the temperature of the air will be raised to a material extent and hence will improve the combustible and expanding character of the fluid mixture that is formed in the carbureter; it being understood in this connection 110 that the carbureter is to be connected in the

ordinary or any other approved manner with a source of hydrocarbon supply (not shown).

The rotor 17 of the compressor 1 is carried by a shaft 18 alined with and coupled at 19 to the shaft 20 of the rotor comprised in my motor, and it will also be noticed here that the valve 8 is carried on a shaft 21 upon which is also carried the rotary portion of a magneto 22, and that the said shaft 20 of the rotor is connected through a reducing train of gears 23 with the shaft 21 and also with a shaft 24 through which latter the rotor is connected with any device 15 that is to be driven.

As shown in Fig. 4, the casing 15 is provided at its opposite ends with exhaust orifices 26 from which conduits, not shown, may lead to a suitable point of discharge.

Disposed in the transverse center of the casing 15 and extending through the lower half of the same is a sump 30, designed to be supplied with oil from a suitable source of supply, and having in its inner curvilinear wall, apertures 31 for conducting oil to the surface against which bear the perimeters of the primary rotor members 32. The apertures 31 are controlled by valves 33, which may be of any type compatible with 30 the purpose of my invention, needle valves being illustrated. At opposite sides of the sump 30 are sumps 34 and 35, Fig. 4; the said sumps being preferably shaped in cross-section as shown, and being spaced apart. 35 The said sumps 34 and 35 are connected to the casing 15 by lag screws 36, Figs. 4 and 7, and each sump 34 and 35 has oil supply apertures 37 in its inner curvilinear wall, controlled by valves 38. The stems of the 40 valves 33 and 38 are equipped with cranks 39, Fig. 2, and said cranks 39 are connected to a common rod 40 so that by manipulating the rod 40 the several valves may be opened or closed in concert. Oil is preferably supplied to each of the said sumps at or adjacent to the highest point thereof.

The rotor members 32 are provided with two groups of spaced blades 50, the said groups being arranged diametrically opposite each other, and each comprising, say, eight or nine spaced blades. The said blades are arranged as shown in Fig. 3, relative to the indicated direction of rotation of the rotor; and it will also be noted that the 55 blades of one member 32 are arranged with their inner ends opposite to spaces between the blades of the other member, so that the expanding fluid in passing through the spaces between the blades of one member will act 60 efficiently against the blades of the other member. This will be better understood when it is stated that the rotor is of the reaction type. Surrounding the rotor members 32 are bearing bands 51 which are dis-

posed in rabbets of the members 32, as shown. The rotor members 32 are arranged together, and at opposite sides of the members 32 are rotor members 52, 53, 54 and 55. Surrounding the rotor members 52 are annular members 56 each of which includes 70 one of the sumps 35 before alluded to, and is therefore stationary in the casing. Each stationary annular member 56 is provided in alinement with the exhaust orifices 26 with a group of, say four, ducts 57, and 75 these ducts 57 are disposed as indicated by dotted lines in Fig. 3 with reference to the direction of rotation of the rotor. Each rotor member 53 is provided with two opposite groups of blades 58, the blades being 80 separated by intervening spaces and being disposed as shown in Fig. 3, relative to the direction of rotation of the rotor. As will be readily appreciated, there is a comparatively large number of the blades 58 in each 85 of the groups of blades carried by the members 53, and the said members 53 are surrounded by bearing bands 59. The rotor members 54 are surrounded by annular members 60 each of which comprises one of 90 the sumps 34. Each stationary annular member 60 is provided in general alinement with the exhaust orifices 26 with a group of ducts 61, each group comprising say, five ducts, as indicated by dotted lines in Fig. 6. 95 The outer rotor members 55 are provided with spaced blades 62, preferably arranged as shown in Fig. 3, relative to the direction of rotation of the rotor, and surrounded by bearing bands 63. It will here be understood that the bearing bands are shrunk on or otherwise suitably affixed to the members 32, 53 and 55, so as to turn therewith.

By comparison of Figs. 3, 4 and 5 of the drawings, it will be appreciated that an ignition of the charge in the explosion chamber 11 is effected when the rotor is in the position shown in Fig. 5, and from this it follows that the blades 50 will travel about sixteen degrees before there is any outlet, 110 the expansion of the gases serving during that time to drive the rotor in the direction indicated by arrow. As the blades 50 of the first group reach the ducts 57, the expanding gases will pass through said ducts and 115 act against the blades of the rotor member 53, after which the expanding gases will of ducts 61 than 57, greater expansion of the blades of the rotor members 55. Because of the employment of a larger number of ducts 61 than 57, greater expansion of the gases will be permitted as the pressure of the same is diminished.

It will be apparent from the foregoing that in the operation of my novel apparatus 125 the spark plugs 12 will be fired alternately, and the magneto will be driven at the same speed as the rotor; also, that the continuing

expansion of the gases until the same reach the exhaust orifices 26 will exert continuing power against the rotor as distinguished from a sudden impulse such as follows the 5 explosion of a fuel mixture. It will further be apparent that my apparatus is of the reaction type, and that incidental to the turning of the rotor through a complete revolution, it is subjected to the action of a plurality of volumes of expanding gases, and 10 that the action of the expanding gases against the rotor is a continuing and uninterrupted operation, for the reason that before one volume of expanding gases has 15 completed its passage through the exhaust orifices 26, the succeeding volume of gases will be acting against the blades 50 of the following group of blades. Again in the time intervening between the volumes of 20 gases against the two groups of blades 50, one of the intervening imperforate portions 75 of the rotor will be opposed to the mouth of the chamber 11 to afford compression in said chamber anterior to the ignition of each 25 volume of combustible mixture.

Having described my invention, what I claim and desire to secure by Letters-Patent, is:

1. An internal combustion apparatus for 30 developing power comprising a casing having aligned exhaust orifices; a combustion chamber in the casing; a rotor mounted in the casing and having a blade-bearing portion opposed to said combustion chamber 35 with the blades in groups and said groups separated by intervening portions for closing the combustion chamber, blade-bearing members at opposite sides of said blade-bearing portion and spaced therefrom and 40 from each other, and stationary members interposed between the blade-bearing portion and the blade-bearing members and having ducts in general alignment with said orifices; a conduit in communication with the 45 atmosphere and arranged in close proximity to the combustion chamber, a carbureter connected with said conduit to receive air therefrom, a compressor connected with the carbureter and operable by the rotor, a valve 50 between and connected with the compressor and the combustion chamber, a magneto operable in concert with said valve by the rotor, and means for igniting volumes of fuel mixture in the combustion chamber during 55 each revolution of the rotor.

2. An internal combustion apparatus for 60 developing power comprising a casing, a driven element therein, a combustion chamber in the casing, a conduit surrounding said chamber in close proximity thereto, ducts connecting said conduit at intervals with the atmosphere, and a carbureter connected with and adapted to receive air from said conduit.

3. An internal combustion apparatus for 65 developing power comprising a casing, a driven element therein, a combustion chamber in the casing, a conduit surrounding said chamber in close proximity thereto, ducts connecting said conduit at intervals 70 with the atmosphere, a carbureter, and a conduit arranged in close proximity to the interior of the casing and connected with the first-named conduit and arranged to supply air to the carbureter.

4. An internal combustion apparatus for 75 developing power comprising a casing, a driven element therein, a combustion chamber in the casing, a conduit surrounding said chamber in close proximity thereto, ducts 80 connecting said conduit at intervals with the atmosphere, a carbureter connected with and adapted to receive air from said conduit, and a compressor for drawing fuel mixture from the carbureter and supplying the same 85 to the combustion chamber.

5. An internal combustion apparatus for 90 developing power comprising a casing, a driven element therein, a combustion chamber in the casing, a conduit surrounding said chamber in close proximity thereto, ducts connecting said conduit at intervals 95 with the atmosphere, a carbureter connected with and adapted to receive air from said conduit, a compressor connected with the driven element and adapted to draw fuel mixture from the carbureter, a valve intermediate of and connected with the compressor and the combustion chamber, a magneto on the same shaft 100 as said valve, a reducing gear intermediate the driven element and said shaft, and means for igniting the fuel mixture in the combustion chamber a plurality of times during each operation of the driven element.

6. An internal combustion apparatus for 105 developing power comprising a casing, a rotor therein, a combustion chamber in the casing and closed at intervals during rotation of the rotor by the rotor, a conduit surrounding said chamber in close proximity thereto and having ducts in communication with the atmosphere, a carbureter connected with and adapted to receive air from said 110 conduit, a rotary compressor connected with the carbureter and actuatable by said rotor, a rotary valve intermediate of and connected with the compressor and the combustion chamber, a magneto on the same shaft as said valve, a reducing gear intermediate 115 of the rotor and said shaft, and means for igniting volumes of fuel mixture in the combustion chamber incidental to each revolution of the rotor.

7. A fluid compressor power apparatus 120 comprising a casing in which is an exhaust orifice, and a rotor mounted in said casing and comprising spaced blade-bearing mem-

bers, in combination with stationary members interposed between the blade-bearing members and having ducts in general alignment with said orifice whereby the expansion of the fluid will exert continuing pressure against the rotor until the fluid passes through said orifice; said stationary members being annular in form and having oil

sumps in their lower portions for supplying lubricant to rotor members disposed therein, 10 and an annular stationary member surrounding the initial blade-bearing member and adapted to supply lubricant thereto.

In testimony whereof I affix my signature.

GEORGE W. CONNOR.
